UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

SEPARATING APPARATUS

Application filed December 31, 1929. Serial No. 417,773.

The present invention relates to apparatus for separating articles from a closely placed series, it being particularly designed for thus operating upon sheets of material such as stacked insoles.

Rubberized insoles for use in making shoes of the tennis- or sneaker-type are sufficiently adhesive so, after they have been dried out and piled upon one another, it will require appreciable effort for the operator to pick them apart to allow their utilization in a lasting operation. An object of my invention is to relieve the operator from this drag upon his work, the sheets being separated automatically and presented to him one by one. In achieving this object, I associate with a magazine or other holder for insoles or like sheet-articles to be separated, movable article-separating means provided with article-engaging portions arranged for movement independently of each other, with one of which portions article-supporting or directing means may be movable. One of the portions is guided in its movement, the guiding and retaining means permitting another portion to move past and away from it, so the two may separate or move relatively to each other. The separating means is shown in the form of a compound blade, the portions of which advance together to enter between adjacent sheets or articles, while the angular separation of the portions removes a sheet from the series in the holder. The adjacent surfaces of the blades may contact, and inclined outer surfaces facilitate the entrance of the compound member between the sheets. To accurately determine the correct point of engagement of the separating blade with the series of articles, there is a gage member movable with the blade and arranged for contact with the sheets, preferably with the side opposite that engaged by the blade or separating means. In the illustrative example of my invention herein disclosed, the sheets to be separated are stacked in a holder,

and a carrier provided with separating means is reciprocated toward and from the stack, and also similarly oscillated. The carrier may be in the form of an arm, the reciprocation of which inserts a blade between the sheets and withdraws it, being produced by the oscillation of an actuating lever, while the oscillation of said carrier relatively to the actuating lever separates the blade-portions and thus a sheet from the stack. A desirable arrangement of the apparatus duplicates the separating means, these being respectively situated adjacent to spaced supports in the magazine for the sheets. This engagement of the articles to be separated at a plurality of points better distributes the applied forces so said articles are more symmetrically positioned upon delivery.

One of the several embodiments which the invention may assume is illustrated in the accompanying drawings, in which

Fig. 1 is a top plan view of my improved separating apparatus;

Fig. 2, a vertical transverse section through the magazine and associated separating elements, the latter being in their normal position; and

Fig. 3, a view similar to Fig. 2 but with the elements in their final delivering position.

The insoles S or other articles to be separated are carried in a magazine M upon the top of a base 10. This magazine is shown as formed in two end-sections, each having vertical V-shaped walls 12, which engage and retain between them the heel- and toe-ends, respectively, of the insoles. Each of these walls 12 rises from a foot-plate 14, which is secured by a slot-and-screw connection 16 to a mounting-plate 18. Screws and thumb-nuts 20, together with dowel-pins 22, attach the mounting-plate to the base, and permit the magazine as a whole to be removed readily and one containing insoles of another size substituted. The connections at 16, 16 allow individual magazines to be adjusted for any

size of insole by a change in the distance between their sections. At the lower portion of each wall 12, near the diverging extremities of the V, is a cross-rod 24, upon which the end-
5 portions of the bottom insole of the contained stack rest. These supports leave between them a space alined with an opening in the top of the base, through which the bottom insoles may be successively removed from the
10 stack.

Extending horizontally between opposite sides of the base, at its top and at the rear of the magazine, is a cross-bar 26, from which extend horizontally bars 28, 28 having slots 15 adapted to guide the ends of a spindle 30. Free to turn upon the spindle, respectively in planes at the inner sides of and adjacent to the supports 24, 24, are two carrier-arms 32, 32. On the upper face of each arm, which is
20 normally held horizontal by connections which will later be described, is the lower portion 34 of a compound separating blade. The upper portion 36 of each blade rests upon the lower, and at its outer extremity has lugs
25 38, through openings in which passes the spindle 30. The width of the portion 36 of each compound blade is such as to engage a considerable length of the insole near the corresponding support 24. The portion 34 is
30 narrower than this, to permit it to move toward and from its companion, while the latter is retained by engagement with its under side near the edges. The adjacent faces of the
35 blades are parallel and in contact, this contact-plane lying, in its normal position, substantially in alinement with the meeting plane of the two lowermost insoles in the stack, while the outer or operating portions of the
40 blades are inclined, converging toward the magazine, the upper portion extending beyond the lower. This relation produces a thin edge upon the separating member readily entering between the stacked insoles, the extension of the upper blade beyond the lower supporting the weight of the stack during the
45 separating movement and minimizing the tendency of the point of the companion blade to catch upon the sheets.

The portions of the separating blade are caused to first travel forward together horizontally with the arm 32 to enter between the two lowest sheets in the magazine, and are then moved about the axis of the spindle 30 to separate the lowest sheet from the body of
50 the stack and deliver it. In the latter action, the blade-portion 34 and the carrier-arm move together, while the portion 36 is restrained from following, remaining raised to uphold the stack between the supports 24 and resist downward displacement during the removal of the terminal sheet. These movements are produced in the following manner: To advance the arms with the blade-portions
55 together, the spindle 30 between the lugs of each blade-portion 36 is engaged by the

slotted upper end of an arm 40 forming a part of a lever L movable in planes between the supports 24, these two arms being fast upon a spindle 42 rotatably mounted transversely of the base. A depending arm 44 of the lever has upon it a roll, which is held by a spring 46, connecting a short arm 48 of the lever to the base, against the periphery of a cam 50. This cam is secured to an actuating shaft 52 journaled horizontally in the base and driven through sprocket-gearing 54 and reducing-gearing 56 from a motor 58. A hand-pad 60 may be provided to govern, through connections 64, a single-rotation clutch 62 controllably transmitting power to the actuating shaft. The effect of the cam 50 upon the lever L is to reciprocate the spindle 30 from one end of the slots in the bars 28 to the other, imparting a corresponding bodily movement to the arm 32 and the separating blade. To separate the lower blade-portion 34 with the carrier-arm 32 from the upper blade-portion 36, each carrier-arm has projecting from it an actuating arm 66, and between the two arms 66 extends a rod 68. This rod, near its center, is joined by a link 72 to a bell-crank lever 74 arranged to turn upon the spindle 42. A roll on the lower arm of the bell-crank is urged by a spring 76, joining the other arm to the base, against the periphery of a cam 78 fixed upon the actuating shaft 52. Thus this cam is caused to oscillate the arms 32 and with them the lower blade-
80 portions 34 toward and from the bottom of the stack in the magazine and in a direction generally longitudinal thereof.

Initially, the blades, with their portions in contact, are carried horizontally by the lever L under the influence of the cam 50, the cam 78 being at this time without effect. Shortly after this travel begins, a roll 80, carried by each arm 32 in advance of the corresponding blade, comes into contact with the lower rear edge of the bottom insole in the magazine and forces its way beneath this. This determines the vertical relation of the upper face of the sheet near its edge, and therefore the location of this face with respect to the reduced edge of the blade, which is secured to the carrier-arm at a definite distance from the roll 80. In this way, the correct entrance of the blade between the adjacent sheets is secured. Since the articles operated upon may vary in thickness, the vertical position of the upper gaging surface of the rolls is made adjustable, each of these turning about an eccentric-stud 82, the angle of each eccentric being capable of alteration by rotating the stud in its arm 32. This is accomplished by an adjusting arm 84 projecting from the stud and provided with a locking pin 86 capable of entering any one of a series of openings 88 in the arms. As such flaccid articles as insoles may sag between the magazine-supports 24, 24, especially as the number in the stack decreases, a

supporting shelf 89 for the central portion of said stack is carried at the forward end of each arm just in advance of the roll 80. The adjacent edges of the shelves are situated in close proximity to each other, nearly bridging the open space at the bottom of the magazine. The upper supporting surface of each shelf preferably lies slightly below the upper gaging surface of its roll 80. Because of this prevention of sinking of the bottom of the stack materially below the gaging surface, relatively slight resistance is offered to the passage of the gage-rolls beneath the sheet to be separated. Thus, location of the point of the compound blade in the plane between the adjacent sheets and its ready entrance along said plane are assured. The blade having been forced between the sheets under the influence of the cam 50 and lever L, the cam 78 comes into action, and, by the bell-crank lever 74 and its connections, begins to swing the arms down about the spindle 30. The blade-portions 34, fixed to the arms, oscillate with them, drawing down from the magazine-supports 24 the bottom sheet, above which it has been inserted. In so doing, each blade-portion 34 passes between retaining and guiding members in the form of rolls 90, 90 turning upon the arms of a yoke 92 depending from the bar 26. During the horizontal travel of the blade, the surface 93 at the under side of the yoke may serve as a guide for the upper blade-portion 36, contact therewith during the approach of the blade to the stack accurately directing said blade in its entrance between the sheets. Each blade-portion 36, first descending from the surface 93 with the companion portion, strikes at its edges upon the rolls 90 and is so held thereby that it continues its reciprocatory movement in a substantially horizontal plane. Thus it maintains the body of the stack against downward displacement under the separating action of the associated blade-portion 34. I prefer to provide for the adjustment of the yoke 92 with the rolls 90 so the movement of the blade-portion 36 may be in the desired plane. For this purpose, each yoke is movable vertically upon the bar 26 by a screw 94 threaded through the center of said yoke, with its head resting upon the upper surface of the bar, while two screws 96, 96, threaded into the bar and bearing upon the yoke, lock the elements in their adjusted positions. As the detached lower sole leaves the stack under the influence of the blade-portions 34, it rests not only upon the gage-rolls 80, but also on rounded upward protuberances or bosses 98 upon the arms at the outer or rear sides of the rolls. It is thus first supported in a substantially horizontal position. Then, as the arms swing down (Fig. 3) about the spindle 30, the separated sole slides over the bosses and rolls and is directed by the shelves 89 to an inclined chute 100 leading to the open front of the base. The delivering end of the chute is divided and has spaced upturned lugs 102, 102. These retain the delivered sole so it may conveniently be grasped and removed by the operator. Instead of producing the separation of each insole by the actuation of the clutch 62 under the control of the operator, the separating apparatus may be driven from the lasting or other machine supplied, in synchronization therewith, or it may be driven continuously at a rate meeting the operator's requirements.

Having described my invention, what I claim as new and desire to secure by Letters Patent of the United States is:

1. In a separating apparatus, a holder for articles to be separated, movable article-separating means provided with article-engaging portions arranged for relative movement independently of one another, and a support for a separated article, said support sharing in the separating movement.

2. In a separating apparatus, a holder for articles to be separated, separating means movable toward and from the holder, said separating means having portions movable together into engagement with the articles and movable relatively to one another to separate the articles, and directing means for a separated article, said directing means being movable with one of the separating portions.

3. In a separating apparatus, a holder for articles to be separated, article-separating means movable toward and from the holder, said separating means having portions movable together into engagement with the articles and movable relatively to one another to separate the articles, and retaining means for one of the portions, said means permitting another portion to move past and away from said retaining means.

4. In a separating apparatus, a holder for articles to be separated, article-separating means movable toward and from the holder, said separating means having portions movable together into engagement with the articles and movable relatively to one another to separate the articles, a guide for the separating means, and means arranged to vary the relation of the guide to the holder.

5. In a separating apparatus, a holder for articles to be separated, separating means movable toward and from the holder, said separating means having portions movable together into engagement with the articles and movable relatively to one another to separate the articles, and a guide for the separating means, said guide having means arranged to retain one of the portions in engagement with an article at the holder and to permit another portion to move away from the holder in effecting the separation.

6. In a separating apparatus, a holder for

- articles to be separated, an article-separating blade having plural portions, means for moving the blade toward and from the holder, means for moving the blade-portions relatively to change their angular relation, and an article-support movable angularly with a blade-portion.
7. In a separating apparatus, a holder for articles to be separated, article-separating means movable toward and from the holder, said separating means having portions movable together into engagement with the articles and movable relatively to one another to separate the articles, and a gage member movable with the blade and arranged for contact with the articles in the holder.
8. In a separating apparatus, a holder for articles to be separated, article-separating means movable toward and from the holder, said separating means having portions movable together into engagement with the articles and movable relatively to one another to separate the articles, a gage member movable with the blade and arranged for contact with the articles in the holder, and means arranged to vary the relation of the gage member to the blade.
9. In a sheet-separating apparatus, a holder for a stack of sheets, a carrier movable toward and from the holder, sheet-engaging members mounted upon the carrier to enter between adjacent sheets, and means for separating the members on the carrier to remove a sheet from the stack.
10. In a sheet-separating apparatus, a holder for a stack of sheets, a carrier movable toward and from the holder, sheet-engaging members mounted upon the carrier to enter between adjacent sheets, said carrier having a gage-surface arranged for contact with the side of a sheet being separated opposite that engaged by the members, and means for separating the members on the carrier to remove a sheet from the stack.
11. In a sheet-separating apparatus, a holder for a stack of sheets, a carrier movable toward and from the holder, sheet-engaging members mounted upon the carrier to enter between adjacent sheets, a gage member mounted upon the carrier and arranged for contact with the sheets, means arranged to vary the normal relation of the gage member to the sheet-engaging members, and means for separating the members on the carrier to remove a sheet from the stack.
12. In a sheet-separating apparatus, a holder for a stack of sheets, a movable carrier provided with sheet-engaging means, means for reciprocating the carrier toward and from the stack, and means for oscillating the carrier toward and from the stack.
13. In a sheet-separating apparatus, a holder for a stack of sheets, sheet-engaging means, means for moving the engaging means between sheets in the stack, and means for moving the engaging means longitudinally of and away from the stack.
14. In a sheet-separating apparatus, a holder for a substantially vertical stack of sheets, a movable carrier provided with sheet-engaging members, means for moving the carrier in a substantially horizontal direction to cause the entrance of the members between sheets in the stack, and means for moving the carrier in a substantially vertical direction to separate a sheet from the stack.
15. In a sheet-separating apparatus, a holder for a stack of sheets, a movable carrier provided with sheet-engaging means, means for reciprocating the carrier into and out of co-operation with the holder, and means for oscillating the carrier with respect to the holder.
16. In a sheet-separating apparatus, a holder for a stack of sheets, a movable carrier provided with a plurality of sheet-engaging members, one of the members being movable on the carrier, means for moving the carrier to effect engagement of the plural members and the sheets, and means for moving the carrier with a portion of the members to separate a sheet from the stack.
17. In a sheet-separating apparatus, a holder for a stack of sheets, a movable carrier provided with a plurality of sheet-engaging members, one of the members being movable on the carrier, means for moving the carrier to effect engagement of the plural members and the sheets, means for retaining a portion of the members in engagement with the stack, and means for moving the carrier with an engaging member to separate a sheet from the stack.
18. In a sheet-separating apparatus, a sheet-magazine, an oscillatory actuating member, a carrier movable by the actuating member and arranged to oscillate relatively thereto, and a sheet-separating blade mounted upon the carrier and movable thereby into engagement with the sheets in the magazine.
19. In a sheet-separating apparatus, a sheet-magazine, an oscillatory actuating member, a carrier movable by the actuating member and arranged to oscillate relatively thereto, and a compound sheet-separating blade mounted upon the carrier and movable thereby into engagement with the sheets in the magazine, said blade having a portion fixed to the carrier and a portion movable thereon.
20. In a sheet-separating apparatus, a sheet-magazine, an oscillatory actuating member, a carrier movable by the actuating member and arranged to oscillate relatively thereto, a sheet-separating blade mounted upon the carrier and movable thereby into engagement with the sheets in the magazine, and a guide against which the forward movement of the carrier forces the blade.
21. In a sheet-separating apparatus, a

- sheet-magazine, an oscillatory actuating member, a carrier movable by the actuating member and arranged to oscillate relatively thereto, a sheet-separating blade mounted upon the carrier and movable thereby into engagement with the sheets in the magazine, a guide against which the forward movement of the carrier forces the blade, and means arranged to vary the relation of the guide to the sheets in the magazine. 5
22. In a sheet-separating apparatus, a sheet-magazine, an oscillatory actuating member, a carrier movable by the actuating member and arranged to oscillate relatively thereto, a compound sheet-separating blade mounted upon the carrier and movable thereby into engagement with the sheets in the magazine, said blade having a portion fixed to the carrier and a portion movable thereon, the movable portion being wider than the fixed portion, and means retaining the wider portion and permitting the passage of the fixed portion. 10
23. In a sheet-separating apparatus, a sheet-magazine, an oscillatory actuating member, a carrier movable by the actuating member and arranged to oscillate relatively thereto and having a gage-surface for contact with the sheet to be separated, a sheet-separating blade mounted upon the carrier and movable thereby into engagement with the sheets in the magazine, and a guide against which the forward movement of the carrier forces the blade. 15
24. In a sheet-separating apparatus, a sheet-magazine, an oscillatory actuating member, a carrier movable by the actuating member and arranged to oscillate relatively thereto, a sheet-separating blade mounted upon the carrier and movable thereby into engagement with the sheets in the magazine, and a gage member adjustable upon the carrier and arranged for contact with the side opposite the blade of a sheet to be separated. 20
25. In a sheet-separating apparatus, a magazine provided with spaced supports for the sheets, sheet-separating means at the bottom of the magazine adjacent to each support, a gage member movable with each separating means, and a sheet-support movable with each separating means and gage member and situated beneath the magazine. 25
26. In a sheet-separating apparatus, a magazine provided with spaced supports for the sheets, a carrier movable toward and from the magazine at the inner side of each support, a sheet-separating blade mounted upon each carrier, and a sheet-supporting shelf projecting from each carrier in advance of the blade. 30
27. In a sheet-separating apparatus, a magazine provided with spaced supports for the sheets, a carrier movable toward and from the magazine at the inner side of each support, a sheet-separating blade mounted upon each carrier, a gage member mounted on each carrier in advance of the blade, and a sheet-supporting shelf projecting from each carrier in advance of the gage member. 35
28. In an insole-separator, a magazine for stacked insoles, a lever co-operating therewith, a carrier-arm pivotally connected to the lever, a separating blade mounted upon the carrier, means for oscillating the lever to force the blade between insoles in the stack, and means for oscillating the carrier-arm relatively to the lever to separate an insole from the stack. 40
29. In an insole-separator, a magazine for stacked insoles, a lever co-operating therewith, a carrier-arm pivotally connected to the lever, a compound separating blade having a portion pivoted upon the carrier-arm and a portion fixed to said arm, means for oscillating the lever to force the blade between insoles in the stack, means for oscillating the carrier to separate the fixed blade-portion from the pivoted portion, and a retaining guide for said pivoted portion. 45
30. In an insole-separator, a magazine provided with spaced supports for the ends of stacked insoles, a lever fulcrumed in a plane between the supports, a carrier-arm pivotally connected to the lever, a compound separating blade having a portion pivoted upon the carrier-arm and a portion fixed to said arm, means for oscillating the lever to force the blade between insoles in the stack, means for oscillating the carrier to separate the fixed blade-portion from the pivoted portion, a retaining guide for said pivoted portion, and means arranged to adjust the guide longitudinally of the stack. 50
31. In an insole-separator, a magazine provided with spaced supports for the ends of stacked insoles, a lever fulcrumed in a plane between the supports, a carrier-arm pivotally connected to the lever and situated below the stack, a separating blade mounted upon the carrier, a gage member mounted upon the carrier below the blade and arranged to contact with the under side of the bottom insole in the magazine, means for oscillating the lever to force the blade between insoles in the stack, and means for oscillating the carrier-arm relatively to the lever to separate an insole from the stack. 55
32. In an insole-separator, a magazine provided with spaced supports for the ends of stacked insoles, a lever fulcrumed in a plane between the supports, a carrier-arm pivotally connected to the lever and situated below the stack, a separating blade mounted upon the carrier, a gage member mounted upon the carrier below the blade and arranged to contact with the under side of the bottom insole in the magazine, an eccentric-mounting for the gage member, means for oscillating the lever to force the blade between insoles in the stack, and means for os- 60

cillating the carrier-arm relatively to the lever to separate an insole from the stack.

33. In an insole-separator, a magazine provided with spaced supports for the ends of stacked insoles, a lever fulcrumed in a plane at the inner side of each support, a carrier-arm pivotally connected to each lever below the stack, a separating blade mounted upon each carrier-arm, a shelf extending from each arm in advance of the blade and toward the opposite arm, and means for oscillating the levers and arms.

In testimony whereof I have signed my name to this specification.

BERNHARDT JORGENSEN.
